UNITED STATES PATENT OFFICE.

ARCHIBALD H. BRINTNELL, OF TORONTO, CANADA.

ANNUNCIATOR.

SPECIFICATION forming part of Letters Patent No. 470,831, dated March 15, 1892.

Application filed April 11, 1891. Serial No. 388,472. (No model.)

To all whom it may concern:

Be it known that I, ARCHIBALD H. BRINTNELL, manufacturer, of the city of Toronto, in the county of York, in the Province of Ontario, Canada, have invented certain new and useful Improvements in Annunciators, of which the following is a specification.

The object of the invention is to design an annunciator, first, in which not only a fire-alarm may be rung and indicated from the thermostat, but in which a trouble or warning alarm will be rung and indicated if any incipient heat or other cause, hereinafter mentioned, should arise which would not be sufficient or capable of ringing or indicating the fire-alarm in the annunciator, but in which, however, should the incipient heat be increased to such a degree as to turn into a fire, the electrical current would pass immediately to the fire-alarm bell and indicator in the annunciator and simultaneously cut off the current from the trouble-alarm bell and indicator, and, secondly, in which a weak-battery alarm would be rung and indicated should the battery to which the wires in the building are connected become weak or any of the battery-wires be cut; and it consists, essentially, first, of operating the trouble-alarm and fire-alarm bells, the trouble and fire alarm indicating levers, and the trouble and fire alarm indicating plates from the armatures of a series of magnets, which armatures are operated by their connection with a closed and an open circuit battery, and, secondly, in providing a supplemental magnet and armature, which armature drops, and a connection with a local battery is formed, which battery operates magnet and armature to ring the weak-battery alarm, the whole being arranged in detail in the manner herein-after more particularly explained.

Figure 1 is a perspective outside view showing the general outside arrangement of my annunciator. Fig. 2 is a perspective interior view, partially in section, with the front removed. Fig. 3 is a plan of arrangement of thermostat-wires and their connection with the annunciator and test-box.

In the drawings like letters and figures of reference indicate corresponding parts.

The annunciator shown is designed for a building of three floors; but it will of course

be understood that my annunciator may be arranged for a building of any number of floors.

55

A is the fire-alarm bell, B the trouble-alarm bell, and C the weak-battery-alarm bell.

D and d are the magnet and armature which operate the fire-alarm bell. E and e are the magnet and armature which operate 60 the trouble-alarm bell, and F and f are the magnet and armature which operate the weak-battery-alarm bell. These bells, with their magnets, armatures, and connections, are of any well-known form adapted to ring 65 continuously so long as the current is unbroken, and it is not thought necessary to show particularly these connections.

G, H, and I are single magnets and are designed to operate the fire-alarm-indicating 70 lever J, trouble-alarm-indicating lever J', and weak-battery-indicating lever J'', respectively.

K, L, and M are the indicating-plates, which are designed to show the number of the flat 75 in which incipient heat, accident to wires, or fire takes place.

K' L' M' are transparent openings made in the front plate of the annunciator to exhibit the plates K, L, and M, respectively, when 80 down on a horizontal position to indicate a trouble or fire alarm. The indicating-plates K, L, and M are secured on the ends of the arms k, l, and m, extending out from the spindles n, journaled in brackets o, forming part 85 of each of the frames p, which support the magnets Q, R, and S.

q is a spiral spring located on the spindle n and so arranged that one end extends over each of the arms k, l, and m, so that the tendency of the spring q is to force each of them downwardly.

r is a stop-arm curved in the form shown. The free end of each of the arms r extends beneath and presses against the bottom of 95 the frame p of each magnet when the indicating-plates K, L, and M are down and holds each indicating-plate vertical opposite its respective opening.

N, O, and P are the armatures of each of 100 the magnets Q, R, and S, respectively.

s is a spiral spring connected at one end to the lower arm of each of the armatures and at the other end to its respective frame p. The

armatures N, O, and P are L-shaped at their lower ends and each has a stop *t* formed on the L-shaped ends, as shown.

5 *u* is a stop against which the end of each L-shaped end of the armatures N, O, and P butts when the armature falls away from its respective magnet.

10 X is a strip of metal extending beneath each of the frames *p*, and Y is a strip extending beneath each of the stops *t*.

15 T and U are the magnet and armature by which the current is thrown from the trouble-alarm-magnet wires to the fire-alarm-magnet wires, and V and W are the magnet and armature by which the current is thrown from the battery wires in the building when the current becomes weak to the local or open circuit battery-wires which pass through the magnet F and operate the armature *f* and its 20 hammer to ring the weak-battery-alarm bell. The magnet T is supported on a frame *g*, and the armature U in its normal position is held away from the magnet by the spiral spring *h*, so that its lower T-shaped end is held against

25 the stop *i*. *j* is a stop situated at the other side of the T-shaped lower end of the armature U. The magnet V is supported on a frame *x* and in its normal position holds the armature W close to it, so that the bottom 30 L-shaped end of the armature is away from the stop *y*.

z is a spiral spring secured at one end to the armature W and at the other to the frame *x*.

35 All of the magnets Q, R, S, T, and V are insulated from their respective frames. The frames *p* of the magnets Q, R, and S, however, are secured on the strip X. The stops *u* also are all located on a strip Y. The continuation 40 of each of the trouble-alarm wires *b* extends into the interior of the annunciator through each of the magnets Q, R, and S to the binding-post Z.

45 *z* is a wire extending from the binding-post Z through the magnet V, thence to the binding-post 3, from which three battery-wires *a'* extend to their batteries and posts 4 in the test-box, from which they continue and complete the circuit with the trouble-alarm 50 wires *b*.

55 *c c* are the fire-alarm wires, connected to and extending from the binding-post 5 in the test-box A' and to each thermostat on each floor to the binding-post *c'* at the top of the annunciator, as indicated, thence running through the magnet T to the binding-post 3, from which the three wires *a* extend to their respective batteries and post 4 in the test-box A'. It will now be seen that three complete 60 circuits are formed by the trouble-alarm and battery wires, and also three complete circuits by the fire-alarm and battery wires.

Should any incipient heat arise in any part of the building, the thermostat in that part 65 immediately throws the electrical current off the wire *b* in that floor—say, for instance, the first flat. The armature N is then drawn by

the spring *s* back from the magnet Q, the L-shaped bottom end of the armature striking against the stop *u*, thus throwing into circuit 70 the local-battery wire *6*, the current passing along the wire *6*, strip *Y*, frame *p*, strip *X*, and wire *6*, which then conducts the current through the frame *g* of the magnet T, the lower part of the armature U, and the stop *i*, 75 from which the current is conducted through the trouble-alarm magnet E, so as to operate the armature *e* and ring the trouble-alarm bell B. The wire *6* then carries the current through the magnet H, the core of which attracts the 80 lever *J'* to it, so as to indicate that there is something wrong in the flat indicated by the drop, and then proceeds to the local battery, thus forming a complete circuit. When the armature is drawn back, as before described, 85 the stop *t* moves away from the end of the curved arm *r*, which, being relieved, is now forced beneath the frame *p* by the spring *q*, which also acts on the arm *k*, forcing it and the indicating-plate K (exhibited by dotted 90 lines in Fig. 2) down into the position opposite the opening K', as shown in this figure. The other indicating-plates L and M, armatures O and P, and magnets R and S, respectively, co-operate in the same way as to each 95 floor of the building. If the incipient heat which causes the thermostat to throw the current off the wire *b* should cease to exist, the current would pass again over the wire *b* and its connecting-wires, as before described, and 100 draw the armature N back to the magnet Q, thereby immediately stopping the ringing of the trouble-alarm bell. The indicating-plate K, however, would still remain down opposite its opening K', so as to indicate that 105 some cause for alarm has taken place. As shown in Fig. 2, the indicating-plates K and L are down opposite their respective openings K' L', so that in these there must consequently be some cause for alarm. Even 110 after the trouble-alarm bell has stopped ringing it will still be clearly shown that some cause for alarm has taken place on the floor indicated by the number appearing in any of the openings K', L', or M'. This insures 115 investigation by the party who has charge of the building, even if he should happen to be away during the period in which the incipient heat has arisen.

The indicating-plate M and armature P on the third floor are shown in their normal position before being actuated.

In Fig. 2 I have not shown any means for restoring the indicating-plates in position, as I do not claim anything in the manner of accomplishing this result; but it will of course be understood that any suitable sliding bar with its attachments similar to those now commonly in use may be used to accomplish the desired result.

Having now shown in detail the mode of operating the trouble-alarm, I shall proceed to describe the fire-alarm system. Should the incipient heat rise to such a degree, or, in

other words, the temperature become so high in the flat or room in which the thermostat is situated that a fire would have commenced, the current is thrown by the thermostat onto 5 one of the fire-alarm wires *c*, through which it passes to the binding-post *c'*, whence it passes by the wire 7 through the magnet *T*, down to the binding-post 8, which is connected by the wire 2 to the binding-post 3, 10 thus completing the circuit. The magnet *T* now draws to it the armature *U*, the lower *T*-shaped end of which is now forced against the stop *j*. The current from the local battery is thus thrown into circuit and passes 15 along through the wire 6, strip *Y*, stop *u*, lower part of the armature *N*, frame *p*, strip *X*, wire 6, frame *g*, lower part of the armature *U*, stop *j*, and then along the wire 9 to the magnet *D*, thereby operating the armature 20 *d* to ring the fire-alarm bell. The current now passes from the magnet *D*, along the wire 9, to the magnet *G*, which draws the lever *J* into the position shown by dotted lines in Fig. 1. The wire 9 then passes to the binding-post 10, 25 thence along the wire 11 to the binding-post 12 of the local-circuit battery, thus forming a complete circuit and operating both the fire-alarm bell and fire-alarm-indicating lever. As the indicating-plate on the first floor, in which 30 incipient heat has first arisen, has dropped into the position similar to that indicated by the plates *K* and *L* in Fig. 2 when the trouble-alarm bell is rung, it will be seen that it will remain in position when the fire-alarm bell is 35 rung and still continue to indicate the floor in which the fire is taking place. As the local-battery current passes along the wire 9 to ring the fire-alarm bell and the lower part of the armature *U* presses against the stop *j*, it 40 will be seen that the local-battery current is thrown off the wires which actuate the trouble-alarm bell and indicating-lever. Consequently the trouble-alarm bell ceases to ring; but the indicating-lever, however, still remains in position until restored by the operator to its 45 normal position. The indicating-plate also remains in position until restored to show the floor in which the heat is now so intense that it would be readily comprehended that a fire 50 must be raging there.

Next in order I shall describe the operation of the mechanism for operating the weak-battery-alarm bell and indicator. As hereinbefore described, the wire 2 from the closed-circuit battery, or battery to which the wires running through the building are connected, runs through the magnet *V*. The armature *W* during this period is held to the magnet *V*; but immediately the current from the closed-circuit-battery wires becomes weak the strength 55 of the current through the magnet *V* is insufficient to support the armature *W*, which consequently falls away from the magnet *V*, the spring *z* bringing the *L*-shaped lower end 60 of the armature *W* against the stop *y*. It will now be seen that a complete circuit will now be formed from the local or open-circuit bat-

tery over the wire 6, which starts from the binding-post 13, connected by wire to the local battery through the strip *Y*, wire 14, frame 70 *z*, lower part of the armature *W*, stop *y*, wire 14, up to the magnet *F*, which actuates the armature *f* and rings the weak-battery-alarm bell *C*. The wire 14 then runs through the single magnet *I*, thus operating the indicating-lever *J*, thence to the binding-post 10, from which it is carried by the wire 11 to the binding-post 12, which is connected by wire to the local battery, as indicated. The weak-battery-alarm bell and indicating-lever are thus actuated 80 immediately upon the current from the main battery becoming weak. If, however, the closed-circuit-battery wire *a* should be cut between the test-box and the annunciator, all the drops would come down, the weak-battery- 85 alarm bell would first be actuated, and then the trouble-alarm bell, and they would both continue to ring until the connection is restored. If the trouble-alarm wire *b* is cut between the test-box and the annunciator, the 90 drop corresponding to the flat would come down and the trouble-alarm bell would ring immediately and continue to do so until the connection is restored. Should the trouble-alarm bell, however, be ringing from incipient heat, it will only continue to do so until the heat has passed away on account of the 95 thermostat and annunciator acting automatically with each other. I may here state that cutting the wires, cross-circuiting, or any 100 other cause by which the current is broken causes the trouble-alarm bell to ring. It will be seen that the fire-alarm bell will never be caused to ring, except by intense heat affecting the thermostat. If any of the fire-alarm 105 wires *c* should be cut, there would still be the trouble-alarm wires, which would actuate the trouble-alarm, and thus give warning to the caretaker of the building that something was wrong on the floor indicated. If any of the 110 trouble-alarm wires were cut, the fire-alarm wires *c* would still be left to give warning at the annunciator. In fact, a double means is provided to insure an alarm being rung at the annunciator. 115

On reference to Fig. 3, it will be understood that by the arrangement of my test-box I can by the switches 15 find out at any moment whether my system is in perfect working order.

From the foregoing description it will be 120 seen that the magnets, with their armatures and mechanism for throwing down the indicating-plates, are operated from the main-circuit battery or battery which supplies the current to the wires which run through the building. The magnets and armatures which 125 respectively throw into circuit the local-battery wires, which through their magnets and armatures operate the trouble-alarm, fire-alarm, and weak-battery-alarm bells and indicating 130 levers, are also operated through the main-circuit battery. It will also be seen from this description that the advantage of my annunciator over those at present in use is that the

caretaker or watchman of the building would always be immediately apprised of the exact kind of alarm which is rung at the annunciator, and may govern himself accordingly.

5. What I claim as my invention is—

1. In combination, the main circuit, including the trouble-alarm wire and the fire-alarm wire, the said trouble-alarm wire including in its circuit a relay to bring into action a local battery when the current on the trouble-alarm wire is thrown off, a thermostat for throwing the current off the trouble-alarm wire and onto the fire-alarm wire, a trouble-alarm and a fire-alarm, each comprising a magnet and armature, the electrical connections between the relay, the trouble-alarm, the local battery, including the armature *U* and the contact *i*, the said fire-alarm wire including the magnet *T* of the armature *U* and the contact *j*, electrically connected with the fire-alarm, substantially as described.

2. In combination, the main battery, the trouble-alarm circuit, and the fire-alarm circuit, with the thermostat for throwing the current from the former to the latter, the relay included in the trouble-alarm circuit, the local-battery circuit controlled by the relay, a trouble and a fire alarm, and electrical connections therefrom to the local battery, including a switch *T U* in the fire-alarm circuit, adapted to cut out the trouble-alarm bell from and cut in the fire-alarm bell to the local circuit when the thermostat directs the current to the fire-alarm circuit, substantially as described.

3. In combination, the main battery, the trouble-alarm wires, including a thermostat to throw the current off of said wire, a relay in the trouble-alarm circuit, controlling a local battery and circuit, a trouble-alarm in said local circuit, and the movable indicating-plate controlled by the armature of the relay to be operated simultaneously with the completing of the local circuit and the ringing of the alarm, substantially as described.

4. In combination, the main battery, the trouble-alarm wires, including a relay, an indicating-plate, and a local battery controlled by the said relay, a trouble-alarm in the local circuit, the fire-alarm wire, the thermostat for throwing the current from the trouble-alarm to the fire-alarm circuit, the fire-alarm, and electrical connections from the fire-alarm wire to the said alarm, whereby upon the presence of incipient heat the trouble-alarm and the indicating-plate will be operated and remain in this position when the current is switched from the trouble-alarm wire onto the fire-alarm wire, substantially as described.

6. In combination, the main battery, the trouble-alarm wire, including a relay, an indicating-plate and a local-battery circuit controlled thereby, a trouble-alarm in the local-battery circuit, the fire-alarm wire, the thermostat for throwing the current from the trouble-alarm wire to the fire-alarm wire, a switch *T U* in the fire-alarm wire, controlling

the battery-circuit leading to the trouble-alarm, and the fire-alarm controlled by said switch.

7. In combination, the trouble-alarm and fire-alarm wires, the thermostat for transferring the current from the trouble-alarm wire to the fire-alarm wire, the series of relays in the trouble-alarm wires, the strips *X* and *Y* in the relay or battery circuit, the strip *X* carrying the frames of the relays and the strips *Y* the contacts by which the local circuit is completed through the strip *X*, the contact, the relay armature and frame, and the strip *Y*, the trouble-alarm, and the fire-alarm, with connections to the relay-battery, substantially as described.

8. In combination, the trouble and fire alarm wires, the said trouble-alarm wires forming closed circuits, the thermostat for directing the current from the trouble-alarm wire to the fire-alarm wires, the series of relays in the trouble-alarm circuits, the trouble-alarm, and the fire-alarm, the switch *T U* in the battery-circuit leading to the trouble and fire alarms, the strips *X Y*, forming parts of the relay-battery circuit and carrying the relays and the contacts, the weak-battery alarm, the magnet *V* in the trouble-alarm circuit, the armature *W*, the contact *y*, and the electrical connections from the said contact to the weak-battery alarm and thence to the relay-circuit and the wire *14* from the strip *X* to the frame of the magnet and armature, substantially as described.

8. The battery and trouble-alarm wires *a* and *b*, the trouble-alarm wire *b* of which runs through each of the magnets *Q*, *R*, and *S* and is designed when the current passes over the complete circuit of the wires to hold the indicating-plate up, but when the current is broken through any one magnet the armature of that magnet is drawn away by the spring *s*, the stop *t* removed from in front of the curved arm *r*, and the indicating-plate is forced down by the spiral spring *q*, as specified.

9. The battery and trouble-alarm wires *a* and *b*, the trouble-alarm *b* of which runs through each of the magnets *Q*, *R*, and *S* and is designed when the current passes over the complete circuit of the wires to hold the indicating-plate up, but when the current is broken through any one magnet the armature of that magnet is drawn away by the spring *s*, the stop *t* removed from in front of the curved arm *r*, and the indicating-plate is forced down by the spiral spring *q*, in combination with the stop *u*, secured on the strip *Y* and coming in contact with its respective armature and conveying the current from the local battery through the wire *6*, strip *Y*, frame *p*, strip *X*, frame *g* of the magnet *T*, lower part of the armature *U*, stop *i*, through the magnets *E* and *H*, and back to the local battery, as specified.

10. The battery and trouble-alarm wires *a* and *b*, the trouble-alarm *b* of which runs

through each of the magnets Q, R, and S and is designed when the current passes over the complete circuit of the wires to hold the indicating-plate up, but when the current is broken through any one magnet the armature of that magnet is drawn away by the spring s, the stop t removed from in front of the curved arm r, and the indicating-plate is forced down by the spiral spring q, in combination with the fire-alarm wire c and auxiliary wire 7, by which the current from the local battery, running through the wire 6, strip Y, frame p, strip X, and frame g of the magnet T, is transferred through the armature U to the stop j, then along the wires 9 and 11, thus completing the circuit to the local battery and operating in its course, by the magnets D and G, the fire-alarm bell and indicating-lever, as specified.

11. The combination, with the wire running from the main-circuit battery and completing the circuit through the magnet V, of the armature W, which when the current over the main wire becomes weak or extinct is drawn by the spring z against the stop y, and the current is thus thrown upon the local-battery wire, which now follows a course through the wire 6, strip Y, wire 14, frame x, lower part of the armature W, stop y, and then proceeds by the wires 14 and 12 back to the battery, operating in its course, as it passes through

the magnets F and I, the weak-battery-alarm bell and indicating-lever, as specified.

12. In an annunciator, an indicating-plate supported on a spindle journaled in brackets 35 on the frame of the magnet and supported in position above the opening by a curved arm, the free end of which presses against a stop formed on the L-shaped lower end of the armature, which is held in position by the current passing through the magnet, as specified. 40

13. In an annunciator, an indicating-plate supported on a spindle journaled in brackets 45 on the frame of the magnet and supported in position above the opening by a curved arm, the free end of which presses against a stop formed on the L-shaped lower end of the armature, which is held in position by the current passing through the magnet, in combination with the spiral spring s, designed to 50 draw the lower end of the armature against the stop, thereby freeing the curved arm from its contact with the stop and allowing the spiral spring q to force the indicating-plate down opposite the opening, in which position it is 55 supported by the free end of the curved arm pressing against the bottom of the frame p, substantially as and for the purpose specified.

ARCHIBALD H. BRINTNELL.
